HARNESS FRAME

Philip L. Spencer, Millbury, Mass., assignor to
Watson - Williams Manufacturing Company,
Millbury, Mass., a corporation of Massachu-
sets

Application January 10, 1939, Serial No. 250,178

1 Claim. (Cl. 139—92)

This invention relates to harness frames used in looms for shedding the warp to produce a desired pattern in the cloth. More specifically, my invention relates to harness frames in which wire or steel heddles are slidably mounted on heddle bars.

These heddle bars commonly extend through and are secured in the side members of the harness frames, and in wide frames they are additionally secured to the top and bottom frame members at a number of intermediate points, as by center posts or studs fixed in said frame members.

15 In order to prevent these studs from limiting the free sliding movement of the heddles when aligning themselves with the warp threads, it has been proposed to use double heddle bars, with the inner heddle bars mounted between the side frame members and secured to the regular heddle bars by a plurality of clips or connections, each of which is freely slidable along both the regular heddle bar and the extra or inner heddle bar, thus avoiding all interference with movement of the heddles along the bars.

20

25 My present invention relates to the provision of an improved clip or connection for the described purpose, which may be easily placed in operative position and which may be as easily removed and replaced in the event of breakage and without derangement of the heddles or warp threads.

More specifically, I provide a one-piece clip or connection which is in part resilient, so that it will yield for removal or replacement but will normally retain its assembled relation with both the regular heddle bar and the extra or inner heddle bars.

My invention further relates to arrangements and combinations of parts which will be herein-after described and more particularly pointed out in the appended claim.

A preferred form of the invention is shown in the drawing, in which—

Fig. 1 is a partial front elevation of a frame embodying my improvements;

45 Fig. 2 is an enlarged front elevation of one of my improved clips;

Fig. 3 is a sectional side elevation, taken along the line 3—3 in Fig. 2; and

50 Fig. 4 is a sectional side elevation, taken along the line 4-4 in Fig. 1.

Referring to the drawing, I have shown a portion of a harness frame comprising a top frame member 10, a bottom frame member 11, side members 12, and regular heddle bars 14 extend-

ing through the side members 12 and secured therein by latches 15.

The heddle bars 14 are also shown as secured to the top and bottom frame members 10 and 11 at a plurality of points by center posts or studs 18, fixed in the frame members and having slots or openings through which the heddle bars extend.

I also provide inner heddle bars 20 on which the wire or steel heddles H are slidably mounted, said heddles being commonly provided with eyes at each end through which the bars 20 are inserted.

The inner bars 20 are connected to the regular heddle bars 14 at a plurality of points by clips or connections 30, one of which is shown in detail in Figs. 2 and 3. Each clip 30 is preferably made from a single piece of sheet steel, and the lower end of each clip, as viewed in Figs. 2 and 3, is provided with an upwardly extending projection 20 31 which defines an inwardly opening slot 32 which slidably receives the inner bar 20.

The upper part of the clip is twisted 90° as shown in the drawing, and the end portion thereof is bent downwardly to form a hook 33, which fits loosely over the heddle bar 14 and which is freely slideable thereon. 25

The clips 30 are preferably tempered, so that the upper ends, together with the hooks 33, are slightly resilient. It will be noted that the ends 30 of the hooks are of such contour that the clips cannot be removed laterally from the bars 14 except by applying enough pressure to bend the hooks 33 slightly outward. This pressure may be easily applied by swinging the clip relative to the 35 heddle bar far enough to open the hook by the necessary amount to release it from said heddle bar.

Before swinging the clip, it is obvious that the bar 20 must be removed from the slot 32, as otherwise no swinging movement can take place. Accidental displacement of the clips is thus effectively prevented. 40

My improved clip is of simple construction and easily manufactured and it is particularly well adapted to its intended purposes. It will be clear from Fig. 4 that the same clip 30 may be used at the bottom of the harness frame as well as at the top, by mere inversion of the clip. 45

Having thus described my invention and the advantages thereof, I do not wish to be limited to the details herein disclosed, otherwise than as set forth in the claim, but what I claim is: 50

In a loom, a clip for connecting double heddle bars comprising a single piece of resilient sheet 55

metal twisted to provide two end portions perpendicular to each other, one of said end portions being bent to provide a yielding hook which slidably receives a first heddle bar, and the other end portion having a relatively wide part provided with an inwardly opening slot to slidably receive the second heddle bar, and said hook being nor-

mally closed around said first bar sufficiently to prevent accidental displacement of said clip transversely from said first heddle bar but being removable therefrom by the application of external force thereto.

PHILIP L. SPENCER.
